UNITED STATES PATENT OFFICE.

FRANK W. SCOFIELD, OF WOODLAND, MICHIGAN.

MASONRY CORNER GUIDE.

Application filed May 13, 1922. Serial No. 560,641.

To all whom it may concern:

Be it known that I, FRANK W. SCOFIELD, a citizen of the United States, residing at Woodland, in the county of Barry and State 5 of Michigan, have invented new and useful Improvements in Masonry Corner Guides, of which the following is a specification.

The object of my said invention is the provision of a simple and easily applied device 10 for use to advantage in the laying of corners in masonry work, this with a view to saving labor and assuring accurate production of a corner.

To the attainment of the foregoing, the 15 invention consists in the improvement as hereinafter described and definitely claimed.

In the accompanying drawings, forming part of this specification:—

Figure 1 is a perspective showing my 20 novel corner guide in use.

Figure 2 is a horizontal section taken through the device in a plane above the spring and also showing the device as applied.

Similar numerals of reference designate 25 corresponding parts in both views of the drawings.

Among other elements my novel device comprises an upright angle member or angle 30 iron 1, i. e., a member of right angle form in horizontal section as definitely appears in Figure 2. On the face of one or both of its portions the said member 1 is provided with graduations 2, spaced apart according to 35 the height of bricks to be incorporated in a wall. Riveted or otherwise appropriately fixed to the upper end of the member 1 are plates 3, disposed at right angles to each other and each equipped with a horizontally 40 disposed spirit level or plumb glass 4.

The said member 1 is designed to be held 45 against downward movement through the medium of a pin 5 disposed immediately under the member 1 and disposed in a mortar portion of a wall.

In association with the member 1 I employ a retractile spring 6 which is relatively arranged as shown and is designed to be maintained in position through the medium 50 of pins 7, the said pins 7 being preferably wedge-shaped and designed to be driven into vertical joints of two wall portions at right

angles to each other. Manifestly when the spring 6 is relatively arranged as shown and described the said spring will straddle the member 1 and thereby hold the member 1 yieldingly to its work and against casual lateral movement in any direction. The plumb glasses or spirit levels 4 have for their function to keep the member 1 plumb each 60 way and to obviate the necessity of handling a mason's level in laying up the corner. In the event of the member 1 being accidentally moved or displaced, the spring 6 will cause the member 1 to spring back to working position, and in this connection it will be noticed in virtue of my improvement it is unnecessary to do any nailing as would be the case if a common straight edge was employed.

Incident to the use of my improvement, the guide member 1 serves to render plumbing unnecessary until the wall is laid to the height of the said member 1. When the wall extends to the top of the member 1, the 75 spring 6 is fastened in the manner described in vertical joints adjacent to the top of the wall, and the member 1 is raised within the spring to the height desired. I would also have it understood that after the wall has 80 been laid to the proper height for the attachment of the member 1, the brick can then be laid to any desired graduation 2, it being understood in this connection that the said graduations 2 indicate the height of the several courses of brick. From this it follows 85 that from the use of my novel device, the necessity of laying up a lead at the corner to line the work by it is obviated.

I have entered into a detailed description 90 of the construction and relative arrangement of the parts embraced in the present and preferred embodiment of my invention in order to impart a full, clear and exact understanding of the said embodiment. I do 95 not desire, however, to be understood as confining myself to the said specific construction and relative arrangement of parts inasmuch as in the future practice of the invention various changes and modifications 100 may be made such as fall within the scope of my invention as defined in my appended claim.

Having described my invention, what I

claim and desire to secure by Letters Patent, is:—

A masonry corner guide comprising an upright angle member adapted to be supported in straddling relation to the corner of a wall and provided at its upper end with plumbing means, a retractile spring strad-

dling the upright angle member and adapted at its ends to be connected to wall portions at right angles to each other, and means for connecting the spring ends to wall portions. 10

In testimony whereof I affix my signature.

FRANK W. SCOFIELD.
